CLAIM

The ornamental design for a mug handle, as shown and described.

DESCRIPTION

FIG. 1 is a top and side perspective view of a mug handle showing my new design;

FIG. 2 is a top plan view thereof;

FIG. 3 is a bottom plan view thereof;

FIG. 4 is a side elevation view thereof, the opposite side being a mirror image;

FIG. 5 is an inner end elevation view thereof;

FIG. 6 is an outer end elevation view thereof; and,

FIG. 7 is a transverse sectional cross-sectional view taken along line 7—7 of FIG. 4.

The broken line showing of a mug in FIG. 1 is for illustrative purposes only and forms no part of the claimed design.
